ELECTRON TUBE

William W. Eitel, Woodside, and Jack A. McCullough, Millbrae, Calif., assignors to Eitel-McCullough, Inc., San Bruno, Calif., a corporation of California

Application October 29, 1945, Serial No. 625,200

2 Claims. (Cl. 250—27.5)

1

Our invention relates to electron tubes, and more particularly to multi-grid tubes, such as tetrodes.

It is among the objects of our invention to provide improvements in the mounting and terminal arrangement for the several electrodes in an electron tube, whereby the tube is better adapted for higher frequency operation.

Another object is to provide improvements of the character described in a tube of the external anode type.

The invention possesses other objects and features of advantage, some of which, with the foregoing, will be set forth in the following description of our invention. It is to be understood that we do not limit ourselves to this disclosure of species of our invention as we may adopt variant embodiments thereof within the scope of the claims.

Referring to the drawing:

The figure of the drawing is a vertical sectional view of a tube embodying the improvements of our invention.

In terms of broad inclusion, our tube comprises a plurality of electrodes and a terminal arrangement therefore, including a grid terminal located on the tube coaxial with and opposite to an anode. In our preferred construction, a pair of coaxial grid terminals are provided, one for a control grid and the other for a screen grid, the screen grid terminal being preferably formed by a metallic header at one end of the tube envelope. The preferred tube includes an external anode having a portion extending into the envelope opposite the header, and also preferably includes a shield interposed between the anode and the control grid terminal.

In greater detail, and referring to the drawing, our preferred tube structure comprises an envelope embodying an external anode 2 so arranged that a portion of the anode extends within the envelope. The anode preferably comprises a tubular metallic body 3 supported on the envelope by a reversely extending flange 4 brazed at one end to anode body 3 and sealed at the other end to vitreous envelope section 6. Anode flange 4 extends upwardly and is spaced from the anode body to provide a reentrant anode structure with a recess formed between the flange and body 3, the flange being preferably curved to provide a downturned sealing rim.

Anode body 3 may be of any suitable metal, such as copper or nickel, and flange 4 is of a metal having an expansion characteristic matching that of the glass in envelope section 6. A metallic tu-

2

bulation 7 secured to the upper end of the cup-shaped anode body provides an exhaust duct. After evacuation, the tubulation is pinched off at tip 8.

5 A plurality of electrodes including a cathode 9, control grid 11 and screen grid 12 are arranged in the envelope to project into anode 3, these electrodes being coaxial with the anode. Cathode 9 is preferably of the filamentary type comprising a helix of thoriated tungsten, it being understood that an indirectly heated type of cathode may be employed if desired. Grids 11 and 12 are preferably of the cage type supported from the bottom and having upper free ends. This free ended electrode structure is important from the standpoint of tube assembly.

A metallic header 13 is provided at the lower end of the tube, opposite the anode, and comprises a dish-shaped piece having a bottom wall 14 and an upturned flange 16 sealed to wall section 6, the header being of a metal having an expansion characteristic matching that of the glass. A central control grid terminal 17 and a pair of cathode terminals 18 and 19 are supported on 20 and insulated from the header. These terminals may be of any suitable construction, those illustrated comprising tubular members extending through apertures in bottom wall 14 and supported by vitreous rings 21 sealed between the tubular members and the header wall.

Cathode 9 is supported on and electrically connected to terminals 18 and 19. A center rod 22 connected to the upper end of the filament has a lateral portion 23 fastened to a stud 24 secured in terminal 19. The lower end of the filament is connected to a sleeve 26 carried by a bracket 27 on an arm 28 fastened to stud 29 secured in terminal 18.

Control grid 11 has its lower end connected to a sleeve 31 carried by bracket 32 on arms 33 fastened to a stud 34 secured in terminal 17. It will be observed that control grid terminal 17 is arranged on the envelope opposite to and in coaxial alignment with the anode, which arrangement is particularly desirable in a tetrode for higher frequency operation.

Screen grid 12 is supported on and electrically connected to header 13, the supporting means for this grid preferably including an electrostatic shield interposed between the anode and the control grid conductor means. The preferred structure comprises a disk-like shield 36 having a central aperture 38 aligned with the screen grid and secured to a mounting ring 37 fastened to the 55 inner surface of the annular header flange 16.

As shown, the lower portions of the screen grid wires are spread somewhat to increase the spacing from sleeve 31, and have outturned ends secured between disk 36 and a washer 38. A slight offset 39 in disk 36 enhances its mechanical rigidity.

By this arrangement the screen grid and connected shield form electrostatic shielding means isolating the anode from the control grid structure. While we prefer to mount the screen grid directly on shield 36, for purposes of simplicity of structure, it is apparent that the screen grid could be extended through aperture 35 and supported separately from the shield. In the latter case the screen grid and shield could be connected, either internally or externally of the envelope.

In the preferred structure illustrated, the header flange 16 provides a terminal ring for the screen grid, which terminal ring comprises part of the envelope side wall and lies coaxial with the anode, so that the control grid terminal and screen grid terminal and anode are all disposed about a common axis suitable for concentric line circuits. Our tube is adapted for plugging into a socket structure, and in order to limit downward movement of the tube in a socket, we preferably form an offset 41 in flange 16 to provide a stop for the socket fingers.

A suitable cooler 42 is secured to the anode for removal of heat. In an air cooled tube, as shown, the cooler comprises a core 43 carrying radial fins 44. Core 43 is of a metal having good heat conducting properties, such as copper, and preferably extends into the recess of the reentrant anode so that removal of heat along the entire outer surface of anode is assured.

An external type of anode is preferred in our tube, because of the greater heat dissipating capabilities of such an anode. While a full external anode may be employed, we prefer to use a type of external anode having portions extending into the envelope. The latter type shortens the overall length of the tube and improves it electrically for higher frequency operation. As illustrated, the anode flange 4 provides a sealing rim which lies above the lower end of the anode, thereby providing ample glass length in section 6 between the anode and grid terminal ring 16 for insulation purposes, while at the same time providing a compact electrode structure with short, low inductance leads to the electrodes. It is understood, however, that certain features of our invention such as the electrode terminal arrangement, may be used to advantage in tubes of the

radiation cooled type (wherein the anode lies wholly within the envelope) as well as in tubes of the external anode type.

We claim:

- 5 1. An electron tube comprising an envelope having an external anode at one end and a control grid terminal coaxial with the anode at the opposite end, an annular screen grid terminal coaxial with the control grid terminal and interposed in the envelope wall between the anode and said control grid terminal, a cathode in the envelope projecting into the anode, a control grid in the envelope surrounding the cathode and connected to the control grid terminal, a screen grid in the envelope surrounding the control grid and connected to the screen grid terminal, and a shield connecting the screen grid and screen grid terminal, said terminal and shield serving to screen the control grid terminal from the anode.
- 10 2. An electron tube comprising an envelope having an external anode at one end, a cathode and control grid and screen grid in the envelope, a control grid terminal on the envelope, an annular screen grid terminal on the envelope interposed between the control grid terminal and anode, said screen grid terminal being coaxial with the control grid terminal, and a shield carrying the screen grid, supported on the screen grid terminal and located between the anode and said control grid terminal, said shield and terminal serving to screen the control grid terminal from the anode.
